(57) **CLAIM**

The ornamental design for a cover of seal cap for reaction chamber of semiconductor, as shown and described.

DESCRIPTION

FIG. 1 is a front, top and right side perspective view of a cover of seal cap for reaction chamber of semiconductor showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof;

FIG. 7 is a left side elevational view; and,

FIG. 8 is a cross-sectional view take along line 8-8 in FIG. 4.
